UNITED STATES PATENT OFFICE.

ALBERT J. LOEPSINGER, OF PROVIDENCE, RHODE ISLAND, ASSIGNOR, BY MESNE ASSIGNMENTS, TO GENERAL FIRE EXTINGUISHER COMPANY, OF PROVIDENCE, RHODE ISLAND, A CORPORATION OF DELAWARE.

AUTOMATIC SPRINKLER SYSTEM.

Original application filed May 19, 1917, Serial No. 169,653. Divided and this application filed November 26, 1923. Serial No. 676,951.

My invention relates to dry-pipe automatic sprinkler systems, and resides in certain features which are hereinafter described as embodied in a sprinkler system wherein 5 the dry-pipe valve comprises an air valve, a water valve and an intermediate chamber, and provision is made for opening the valve by admitting fluid under pressure to the intermediate chamber, this application being 10 a division of my prior application Serial No. 169,653, filed May 19, 1917, in which a system having the characteristics above referred to is described and claimed.

In the accompanying drawing the figure 15 illustrates such parts of a sprinkler system as will suffice for an understanding of my invention, the constructional features being shown partly in side elevation and partly in vertical section.

20 In the drawing, 2 indicates the lower portion of a riser, which may be assumed to form a part of a system of sprinkler pipes provided with the usual heads, and 3 indicates a dry-pipe valve interposed between 25 the lower end of the riser 2 and the water supply pipe 4. The particular dry-pipe valve illustrated is constructed and adapted to operate in the manner shown and described in U. S. Letters Patent No. 1,196, 30 875, granted September 5, 1916, and comprises an air valve 5 carried by an arm 6 which is pivotally mounted within the valve casing, a water valve 7 carried by the air valve 5, and valve seats 8 and 9 on which the valves 5 and 7 are respectively seated 35 under normal conditions and which are separated by an intermediate chamber 10. To this chamber is connected, as is customary in dry-pipe valves, a normally-open drip attachment 11 which takes care of any 40 leakage into the chamber 10 and automatically closes when fluid under pressure enters the chamber.

Between the intermediate chamber 10 and the water supply pipe 4 are connections consisting, in the construction illustrated, of a 45 receptacle 12 connected to the chamber 10 by a pipe 13 and to the supply pipe 4 by a pipe 14, these connections being normally 50 closed by means of a valve 15, shown as a pivoted gravity valve located within the receptacle 12. The receptacle 12 also contains a weighted valve-opening lever 16, normally maintained in upright position as

hereinafter described and provided at its 55 lower end with a finger 17 located beneath the free end of the valve 15, so that when said lever falls it opens the valve. Adjacent to the upper end of the lever 16, and in position to be engaged by it, is located 60 the downwardly-extending lower end of a movable member 18 consisting of a rigid bar interposed between and connected to the adjacent ends of two opposed pressure-operated devices 19 and 20 contained within 65 the receptacle 12, each of which is shown as consisting substantially of a cylindrical bellows made of thin sheet metal and deeply corrugated circumferentially, so that it is adapted to be lengthened or shortened by 70 change of pressure applied thereto. One of these pressure-operated devices, as 19, is directly connected internally to the sprinkler pipe system by means of a pipe 21, while the other device, 20, is connected internally 75 to an air pressure receptacle 22 which in turn is connected to the sprinkler pipe system by a pipe 23.

The rate of flow of air through the pipe 23 is restricted by a small orifice 24 through 80 which the air has to pass and which is of such size that while it is adequate to maintain equal pressures in the sprinkler pipe system and the receptacle 22 in case leakage of air from the system occurs, it is incapable of keeping the pressures equal in 85 case the pressure in the system is reduced by the opening of one or more sprinkler heads. Consequently, while under static 90 conditions the air pressure in the sprinkler pipe system and the receptacle 22 are always the same, the opening of one or more 95 sprinkler heads has the effect of immediately unbalancing these pressures, leaving the pressure in the receptacle greater than that in the sprinkler pipe system, and as a result of the differential pressure thus created the bellows 20 lengthens and the bellows 19 shortens, thereby moving the bar 18 laterally.

100 The orifice 24 is shown as formed in the inner end of a plug 25 screwed into a casting 26 which is interposed between the receptacle 22 and the pipe 23 and is divided internally into two separate chambers 27 and 28. The inner portion of the plug 25, which enters the chamber 27, is made hollow and provided with lateral perforations

29 so located that when the plug is in place they communicate with an annular groove 30 connected by a passage 31 with the chamber 28, the capacity of the several passages to transmit air being determined by the size of the orifice 24. With this arrangement, the plug 25 can be conveniently removed for the purpose of inspecting the condition of the orifice 24 and cleaning it in case it 10 has become clogged by dirt blown into it from the sprinkler pipe system when the apparatus is charged with compressed air. In order to minimize the danger of clogging the orifice 24 the chamber 28 is preferably 15 divided by a strainer 32 contained therein, through which the air has to pass before it reaches the plug 25.

Assuming that the water supply has been 20 shut off and the dry-pipe valve closed, the parts above described are put into condition for operation by opening the receptacle 12, which has a removable portion 33, and swinging the lever 16 upward until its upper end rests against the bar 18, the normal 25 position of which is such that when the upper end of the lever 16 is in contact with it said lever is held by gravity against the bar, with its center of gravity located nearly 30 above its pivot. The valve 15 is then closed by gravity, and after closing the receptacle 12 air is pumped into the sprinkler pipe system until the normal pressure is established 35 therein. While this pressure is being built up the pressure within the bellows 19 will 40 slightly exceed that within the bellows 20 on account of the effect of the orifice 24 in restricting the flow of air to the receptacle 22, so that the bar 18 will be moved somewhat to the right with reference to its normal 45 position illustrated, but since such movement is in the direction towards which the weighted upper end of the lever 16 tends to move under the action of gravity said lever will merely follow the bar and will ultimately 50 be restored to its normal position as soon as the pressure within the receptacle 22, and therefore within the bellows 20, is equalized with that in the sprinkler pipe system. The water supply is then turned on 55 and water under the supply pressure immediately enters the receptacle 12 through the pipe 14, but no change in the position of the bar 18 results because the water pressure acts equally on the exteriors of both the bellows 19 and 20, so that the lever 16 retains its normal position and the valve 15 remains closed.

The system having thus been put in its 60 normal or static condition, a slow reduction of pressure in the sprinkler pipe system, such as may result from a leak, will have no effect on the bar 18, because the pressures within the bellows 19 and 20 will diminish at the same rate, but a quick reduction of 65 pressure such as results from the opening

of one or more sprinkler heads will unbalance the pressures within the bellows 19 and 20 as above explained, and the resulting lateral movement of the bar 18 will carry the upper end of the lever 16 past its dead-center position, whereupon said lever will fall and in falling will acquire sufficient kinetic energy to open the valve 15 against the water pressure in the receptacle 12. Thereupon 70 said pressure will immediately be made effective in the intermediate chamber 10 by the passage of water at the service pressure through the pipe 13, the drip valve 11 will automatically close and the pressures acting on the water valve 7 above and below it will 75 immediately be equalized, and consequently the dry-pipe valve as a whole will become in effect a mere check valve and will be opened by the service pressure, even though the air pressure in the sprinkler pipe system has 80 been but slightly reduced from its normal amount. 85

It will be seen that the opening of the dry-pipe valve in the system above described is materially accelerated, as compared with a 90 system in which the valve cannot open until the system pressure which normally holds it closed has become insufficient for that purpose, but the means by which this result is accomplished are not broadly claimed herein, 95 being claimed in my prior application above referred to. The invention forming the subject matter of the present application resides in the features and combinations hereinafter claimed, relating to the opening of the dry-pipe valve by the admission of water under 100 pressure to the intermediate chamber, and to the pressure-operated devices which respond to a quick drop in pressure in the 105 sprinkler-pipe system. It will be evident that the utility of these devices is not limited to the control of fluid pressure derived from any specific source, and that they may be constructed and combined with the associated parts of a dry-pipe sprinkler system 110 in various ways without departing from my invention. 115

I claim:

1. In an automatic sprinkler system, the combination of a dry-pipe valve normally held closed by fluid pressure in the system and comprising an air valve, a water valve and an intermediate chamber, and means operative upon the opening of one or more 115 sprinkler heads for admitting water under pressure to the intermediate chamber. 120

2. In an automatic sprinkler system, the combination of a dry-pipe valve normally held closed by fluid pressure in the system and comprising an air valve, a water valve 125 and an intermediate chamber, connections between the intermediate chamber and the water supply system, a normally-closed valve controlling said connections, and means operative upon the opening of one 130

or more sprinkler heads for opening the latter valve.

3. In an automatic sprinkler system, the combination of a dry-pipe valve normally held closed by fluid pressure in the system and comprising an air valve, a water valve and an intermediate chamber, connections between the intermediate chamber and the water supply system, a normally-closed valve controlling said connections, and means rendered operative by a quick reduction but not by a slow reduction of the system pressure for opening the latter valve.

4. In an automatic sprinkler system, the combination with a dry-pipe valve of two pressure-operated devices separately connected to the sprinkler pipe system on the distributing side of the dry pipe valve, flow-restricting means included in the connections leading to one of said devices, a member connected to said devices and movable thereby when said devices are subjected to different pressures, a connection leading to the intermediate chamber of the dry pipe valve from a source of fluid pressure other than the pressure on the distributing side of the dry pipe valve, means normally maintaining the last said connection closed, and means operated by said movable member for effecting the opening of the last said connection, thereby to effect opening of the dry pipe valve.

5. In an automatic sprinkler system, the combination with a dry-pipe valve of two expansible devices separately connected to the sprinkler pipe system on the distributing side of the dry pipe valve and adapted to expand in opposite directions on increase of the internal pressure therein, flow-restricting means included in the connections leading to one of said devices, a movable member interposed between said devices and connected thereto, a connection leading to the intermediate chamber from a source of fluid pressure other than the pressure on the distributing side of the dry pipe valve, means normally maintaining the last said connection closed, and means operated by said movable member for effecting the opening of the last said connection, thereby to effect opening of the dry pipe valve.

6. In an automatic sprinkler system, the combination with a dry-pipe valve of two pressure-operated devices each consisting substantially of a cylindrical bellows, connections leading from the interior of each bellows to the sprinkler pipe system on the distributing side of the dry pipe valve, flow-restricting means included in one of said connections, a movable member adapted to be operated by said bellows when subjected internally to different pressures, a source of fluid pressure other than the air pressure of the sprinkler system, having connection with the intermediate chamber of

the dry pipe valve, means normally maintaining the last said connection closed, and means operated by said movable member for effecting the opening of the last said connection, thereby to effect opening of the dry pipe valve.

7. In an automatic sprinkler system, the combination of a dry-pipe valve normally held closed by fluid pressure in the system and comprising an air valve, a water valve and an intermediate chamber, normally-closed connections between the intermediate chamber and the water supply system, two pressure-operated devices separately connected to the sprinkler pipe system, flow-restricting means included in one of the latter connections, and means operated by said device for opening the connections between the intermediate chamber and the water supply system.

8. In an automatic sprinkler system, the combination of a dry-pipe valve normally held closed by fluid pressure in the system on the distributing side of the dry pipe valve and comprising an air valve, a water valve and an intermediate chamber, a receptacle connected to the intermediate chamber and to a supply of fluid under pressure other than the pressure holding the dry pipe valve closed, a normally-closed valve located in said receptacle and controlling said connections, two bellows contained in said receptacle and separately connected internally to the sprinkler pipe system, flow-restricting means included in the connections leading to one of the bellows, a movable member connected to said bellows, and means operated by said movable member for opening the last-mentioned valve.

9. In an automatic sprinkler system, the combination of a dry-pipe valve normally held closed by fluid pressure in the system and comprising an air valve, a water valve and an intermediate chamber, a receptacle connected to the intermediate chamber and to the water supply system, a normally-closed valve, located in said receptacle and controlling said connections, two bellows contained in said receptacle and separately connected internally to the sprinkler pipe system, flow-restricting means included in the connections leading to one of the bellows, a weighted arm normally maintained in elevated position and arranged to open the last-mentioned valve when it falls, and a movable member connected to the bellows and adapted to operate said weighted arm.

10. In an automatic sprinkler system, the combination with a dry pipe valve of two fluid pressure-operated devices separately connected to the sprinkler pipe system and opposing each other; flow-restricting means included in the connection leading to one of said devices; a movable member adapted to be moved by one of said devices when said

devices are subjected to different pressures; a conduit to the intermediate chamber of the dry pipe valve for fluid under pressure; a valve controlling said conduit; and means operated by said movable member for opening said conduit valve and thereby effecting the opening of the dry pipe valve; the whole

being arranged with said fluid pressure in the conduit neutral in its effect on the said movable member.

10

Signed at Providence, Rhode Island, this 22nd day of November, 1923.

ALBERT J. LOEPSINGER.
